UNITED STATES PATENT OFFICE

155,106

DESIGN FOR A TOY BABY-WEIGHING SCALE

Adele E. Rogovin, New York, N. Y.

Application October 31, 1947, Serial No. 142,241

Term of patent 3½ years

(Cl. D34—15)

To all whom it may concern:

Be it known that I, Adele E. Rogovin, a citizen of the United States of America and resident of the city of New York, State of New York, has invented a new, original, and ornamental Design for Toy Baby-Weighing Scale, of which the following is a specification, reference being had to the accompanying drawing, forming part thereof, in which,

Fig. 1 is a front elevational view, partly in perspective, of a toy baby-weighing scale embodying my new design;

Fig. 2 is a top plan view thereof, but of reduced size;

Fig. 3 is a side elevational view of the scale shown in Fig. 2; and

Fig. 4 is a rear elevational view thereof.

I claim:

The ornamental design for a toy baby-weighing scale, substantially as shown.

ADELE E. ROGOVIN.
